UNITED STATES PATENT OFFICE.

JOSEPH ROTH AND WILLIAM HELMKE, OF LONDON, ENGLAND, ASSIGNORS
OF ONE-THIRD TO GEORG MAETZOLD, OF SAME PLACE.

RAILWAY SIGNALING.

SPECIFICATION forming part of Letters Patent No. 681,377, dated August 27, 1901.

Application filed March 2, 1901. Serial No. 49,541. (No model.)

To all whom it may concern:

Be it known that we, JOSEPH ROTH, residing at 33 Little Alie street, and WILLIAM HELMKE, residing at 27 Colchester street, in Leman 5 street, White Chapel, London, E., England, subjects of His Majesty Edward VII, King of Great Britain, have invented new and useful Improvements in Railway Signaling, (for which we have applied for patent in Great Britain, No. 20,423, dated November 13, 1900, and in Germany, dated February 5, 1901,) of which the following is a specification.

Our invention relates to an improved system of and apparatus for signaling upon 15 steam, electric, and other railways in fine and foggy weather, the most important object of our said invention being to provide means whereby the employment of special hands or "foggers" in foggy weather may be dispensed 20 with, thus obviating the possible hazard to life and limb which so frequently obtains during the employment of such special hands or foggers; and we attain the objects of our invention by providing at certain parts of the 25 track or tracks—such, for instance, as at or near the home or distant signals or at or near a level crossing or at or in a station—fixed and movable bars placed parallel with the track-rails, such bars being adapted to actuate 30 a sonorous or any other signal upon the engine of the passing train for the purpose of conveying to the driver thereof such information as is now conveyed by the explosion of the detonator as at present used.

35 In order that our said invention and the manner in which the several parts operate for their respective purposes may be fully understood, we have hereunto appended five sheets of drawings, of which—

40 Figures 1, 2, and 3 are plan views of certain parts of a railway-track arranged according to our invention, the arrangements shown by Figs. 1 and 3 being stationary, while the arrangement Fig. 2 is movable or operative 45 under the conditions and in the manner hereinafter explained. Fig. 4 is an enlarged vertical sectional view taken upon the line A B or thereabout of Fig. 2. Fig. 5 is a further enlarged view of the details by which the 50 movements of the movable bar in Fig. 2 are effected. Fig. 6 is a diagram illustrating a

form of weighted lever that we may employ in lieu of the weight shown in Figs. 2 and 4. Figs. 7, 8, 9, and 10 are views similar to Figs. 1, 2, 3, 4, and 5, but illustrating an alternative method of operating the weighted and movable parts. Fig. 10 is a further-enlarged view similar to Fig. 4, while Fig. 11 is a view similar to Fig. 5, but both relating to the device shown by Fig. 8. Fig. 12 is a plan view 60 of a portion of a railway-track within a station, illustrating an improved arrangement of a locking-bar operating upon a distant or home signal, or both, Fig. 13 being an enlarged sectional view taken upon the line C D 65 of Fig. 12. Fig. 14 is an enlarged part-sectional view illustrating the normal position of the locking-bar relatively to the track-rail, while Fig. 15 illustrates the position of the said bar when depressed by the wheels of any 70 one of a train of vehicles. Figs. 16, 17, and 18 are side elevational views of a locomotive, illustrating various positions of the operating-lever under a variety of conditions hereinafter explained. Fig. 19 is an enlarged 75 detached view of the pivoted signaling-arm within the cabin of the engine actuated by the said lever, while Figs. 20, 21, and 22, respectively, are enlarged views of the said lever, as shown in Figs. 16, 17, and 18, respectively. Fig. 23 is an enlarged diagram showing the relative positions of the track-wheels of a locomotive upon the track-rails and the operating-lever when upon one of the bars, as hereinafter fully explained. Fig. 24 is a dia- 80 grammatic view, and Figs. 25 and 26 detail views, of sonorous signals.

We are informed that upon certain steam, electric, and other railway systems in foggy weather it is customary to give three sonorous 90 signals when the line is "blocked" and the train is to stop and two when the line is "clear" and the train may proceed, while other systems arrange that two detonators exploded shall mean line blocked and one 95 that the line is clear, and we therefore wish it understood that although in the accompanying drawings we have chosen to illustrate our invention as arranged for the "3" and "2" system, we may by simply doing away 100 with one of the stationary bars adapt precisely the same arrangement to a "2" and

"1" system without in any way departing from the principle involved and forming the substance of our invention.

Referring to Figs. 1, 2, 3, 4, and 5, we carry our invention into effect by providing at or near to a home or distant signal or both and at a suitable distance from each other two fixed bars, such as *a* and *b*, Figs. 1 and 2, placed parallel with, outside of, and at a suitable distance from the (preferably) near-side track-rail *c*, and midway or thereabout between the said bars *a* and *b* we provide a third and movable bar *d*, Figs. 2 and 4, also parallel with the same track-rail *c*. The said bar *d* is preferably arranged to slide laterally within guides *e e* and upon track-plates *ff*, so that the said bar may be brought as near to the track-rail *c* as the bars *a b* or farther therefrom at will. The said bar *d* has connected to one side thereof two or more ropes, lines, wires, or chains *g g*, which pass therefrom under suitable guide-wheels *h h* and from these upwardly over other guide-wheels *h h* upon posts *j*, the opposite or free ends of *g g* being then connected to weights *k*, the pull from which serves to keep the said bar *d* away from the track-rail *c* and in the position shown by full lines in Figs. 2 and 4, or in lieu of the said guide-wheels *h h* and weight *k* we may provide that after passing the guide-wheels *h h* the free ends of *g g* may be connected to the one end of adjustable weighted levers *k k*, as illustrated by Fig. 6, the pull given from this being an equivalent of that given by the weights *k*.

The opposite side of the bar *d* has connected thereto the one end of a pair of cords, wires, ropes, or chains *l l*, which, passing under the wooden stagings *x*, (usually provided at such parts of railway-tracks,) are led around suitable guide-wheels *m m*, whereat they may be joined to form one, as at *l l*, which is then continued around or over or under other guide-wheels *m m* and is led away to the nearest signal-cabin or other signaling place, whereat a pull may be imparted to *l l* in the direction of the arrow in Fig. 2 either alone or by means of the same lever as operates the semaphore at the same point, which would serve to bring the bar *d* into the position shown by dotted outline in Figs. 2 and 4 against the tensional pull of the weights *k k* or weighted levers *k k*.

In Figs. 7, 8, 9, 10, and 11 we illustrate a slight modification of the foregoing and in which the force of the weights employed and a pull upon the chain, wire, or the like *l l* operates upon the bar *d* in reverse order to that previously described. For the purposes of this arrangement we pivotally connect to the one or outer side of the bar *d* the one end of two or more rods *n n*, the opposite ends of which are pivotally connected to the one end of lever-arms *O O*, pivotally mounted upon standards *O'*, the outer or free ends of which said levers are provided with weights *p p*, which normally rest upon suitable supports

p p and serve to keep the rail *d* in its closest position to the near rail *c*, as shown by full lines in Figs. 8 and 11. The bar *d* has also connected thereto the one end of the cords, wires, or the like *l l*, which pass therefrom through guide-wheels and are joined to form one *l l*, as before, which is then led over, under, or through suitable like guides to the nearest signal-cabin or other signaling place, as may be arranged, a pull upon the said cord or the like *l l* in the direction of the arrow, Fig. 11, serving to pull the bar *d* from the position shown by full lines to that shown by dotted outline in Figs. 8 and 11, such pull being against the force of and serving to raise the weights *p p* from the position of rest upon their supports *p p* to that shown by dotted outline in Fig. 10, the said weight serving to reinstate the bar *d* as soon as such pull upon *l l* is released.

Referring to Figs. 16 to 23, inclusive, we for the purposes of our invention provide upon either or both sides of the locomotives *r a* lever-arm *1*, pivotally mounted at a point *2*, preferably in such a manner that its lower and depending end (provided with a wheel or roller *3*) extends through a slot in the foot-plate *r r* of the engine, while its upper end is pivotally connected to an arm *4*, from which point the said arm passes through a slot or gap in the front of and into the cab *r* of the locomotive, whereat it passes through a slot 5 in a vertical arm *6*, the lower end of which is pivotally mounted at a point *7*. The said arm *4* is provided at its free or inner end with any suitable form of handle or handhold *8*, at a suitable distance from which the said arm has on its under surface two cut-away parts or slots *9* and *10*, either of which at the will of the driver may be caused to engage with the substance at the lower end of the slot 5 in the arm *6* in the manner and for the purposes now to be described.

In clear weather, when the semaphore and other usual signals are to be easily seen by the driver, the arm *4* would be placed in the position shown by Figs. 16 and 20—that is to say, with its cut-away portion or slot *10* engaging with the substance at the bottom of the slot 5 in *6*—whereat it may be retained by any suitable means—such, for instance, as by that of a spring, as suggested by dotted outline at 11, Fig. 20, or by that of a wedge (not shown)—and while *6* is in this position the lever-arm *1* would take the position shown in Figs. 16 and 20—that is to say, with its roller or wheel *3* raised perfectly clear of both the stationary bars *a* and *b*; but directly the driver finds himself entering foggy or hazy weather, when it may not be possible for him to clearly discern the semaphores ahead, he would change the position of the lever-arm *1* so that its slot or cut-away portion *9*, and not 11, engages with the substance at the bottom of the slot 5 in *6*, which would have the effect of placing the lever *1* in an approximately vertical position or substantially

as at Figs. 17 and 21, its lower end or wheel 3 being then in such a position as to collide with both the bars *a* and *b*, as at Fig. 21, and ride thereover, as at Figs. 22 and 23, 5 and such impact with each of the said bars would deflect the lever 1, and this in turn would deflect the vertical arm 6, as shown in Figs. 18 and 22, these remaining so deflected during the whole time the wheel 3 is passing 10 over each of the said bars, after which it would return to its former position, as at Figs. 17 and 21. It will thus be seen that unless the central and movable bar *d* has been operated upon from the signal-cabin or other 15 place the two bars *a* *b* would be the only ones with which the lever 1 would collide, which (as set out in the preamble hereof) would mean "line clear," and the driver would proceed; but if the line be blocked 20 and the signalman had operated upon the movable center-bar *d* in either of the manners stated such center-bar would be placed in the position shown by dotted outline in Figs. 2 and 4 and by full outline in Figs. 8, 25 10, and 11, and in alinement with the fixed bars *a* *b*, when in consequence of the lever-arm 1 and vertical arm 6 of the locomotive being deflected by wheel 3 of the former coming in contact therewith it follows that the vertical 30 arm 6 would be deflected three times by the engine passing over *a*, *d*, and *b*, and such three deflections would (by the arrangement hereinbefore provided for) intimate to the driver that the line was blocked and that 35 the train must not pass the semaphore adjacent to which the bar *b* would be located, so that the driver might see or hear when this fell, so as to know when to proceed.

In order that the driver may not have to 40 depend upon his eye alone to know when such deflection of the vertical arm 6 takes place, we may arrange that such deflection of the arm 6 may strike a bell within the cab *r'*, or we may by attaching to the upper end of 6 a cord, 45 wire, or chain 12, as shown in Figs. 19, 20, 21, and 22, impart by such deflection a pull upon such cord or the like arranged to operate any form of sonorous signal within or without the cab *r'*—such, for instance, as that 50 of operating mechanically the striker of a bell or to operate to open the whistle of the engine or to close the circuit of an electric bell—in addition to which such pull upon the cord 12 may operate upon whatever device may be 55 in use for shutting off the steam (or switching off the current, if electrically driven) as an aid to the stopping of the train.

The cord, chain, or wire 12 may under certain conditions be arranged to be pulled by 60 and from the gate of a level crossing when opened in order to operate upon the center and movable bar *d* of a distant device *a* *b* *d* in foggy weather or the semaphore adjoining it in fine weather, so as to arrest the progress of a coming train while such gate is open, 65 thus operating to save probable loss of life should a horse have fallen in crossing the line

or other accident have occurred while the gate is open.

In Figs. 12, 13, 14, and 15 we illustrate the 70 manner in which we provide that a train standing at rest in a station may operate upon a "locking-bar" for imparting a pull upon a rope, wire, or chain, such as *b*, leading to and connected with a distant bar *d* or semaphore to signal to an oncoming train that a 75 train is in the station, such locking-bar by locking such distant bar or semaphore serving to prevent possible errors on the part of the signalman. For the purposes of this part 80 of our invention we provide within the station a locking-bar *v*, placed between and parallel with the track-rails *c* *c* and sufficiently near to one or the other as to be depressed by the flanges of the wheels of trains. The 85 said locking-bar *v* is supported by any number of vertical attached rods 13, the lower end of each of which rests upon a suitable spring 14 within a sunken metallic or other box 15, the tensional force of such springs 90 serving to keep the said bar *v* in its highest position, level, or thereabout, with the adjoining track-rail. At a point 16, Fig. 13, adjacent to one of the rods 13 and below the said locking-bar, is pivotally mounted a lever *w*, the inner and shorter end of which is pivotally connected at a point 17 to its rod 13, while its outer end is connected to one end of a rope, wire, chain, or cord *l*, which from this point is led over, under, or around 100 suitable pulley or other guides *m*, its opposite end being connected to a distant or home signal bar *d* or to a semaphore near to the accompanying bar *b*, or both. By reference to Fig. 14 the normal position of the said 105 locking-bar *v* will be understood, while Fig. 15 conveys a perfect knowledge of the manner in which the said locking-bar is depressed and retained so depressed by the track-wheels 110 *y* of any portion of a train within the station, such depression of the locking-bar operating to lower the inner and shorter end of the lever *w*, the consequent raising of the outer end thereof (indicated by dotted outline in Fig. 13) operating to impart a pull upon the 115 cord or the like *l*, such pull serving to place the before-mentioned distant or home signal bar *d* or semaphore, or both, in a position or positions to indicate to the driver by sight or sound that a train is within the station, and 120 directly the train departs and its weight is removed the said locking-bar would rise to its normal position by the tension of the springs 14, when the outer end of the lever *w* would lower and the pull upon the cord or the like *l* 125 be released, and thereby allow the said distant or home semaphore or bar *d*, or both, to return to their normal positions. By these means a train entering a station may be arranged to automatically operate to place at "danger" 130 and lock both the distant or home semaphore for sight-signaling in fine weather and the distant or home signaling bar *d* and semaphore in foggy weather, by which means pos-

sible disaster through neglect of duty on the part of the signalman is averted and the objects and purposes of our invention attained.

Having now particularly described and ascertained the nature of our said invention and in what manner the same is to be performed, we declare that what we claim is—

1. The improved apparatus for railway signaling, consisting of the combination of one or two fixed signaling-bars such as *a* and *b*, and a movable signaling-bar such as *d*, the latter arranged to slide upon suitable guides parallel with the track-rails *c*, the said bar *d* when actuated by and from a station, level crossing, or signal-cabin, or and by suitable weights or levers, being placed in such a position as to collide with a lever *1* upon the locomotive of a passing train, such lever actuating an arm *d* previously placed by the driver in a suitable position within the slot 5 of a lever *6*, the deflection of lever *6* operating to shut off the motive power and stop the train, or and to excite the mechanical, electrical or other sonorous signal, in use substantially as and for the purposes herein described and shown.

2. The improved apparatus for automatically actuating home or distant signals upon a railway, by and from the actual presence of

a train within a station, consisting of the combination of a locking-bar *v*, placed within the station near to a track-rail *c*, and supported upon springs such as 14, the said bar being adapted to be depressed by the track-wheels of a train, the rise and fall of such bar actuating a lever *w* adapted to impart a pull upon a wire, cord, chain, rope or the like *z*, for operating a distant semaphore, or for placing a distant signaling-bar *d* in a position to operate in concert with fixed bars *a* or *b* or both, for deflecting a lever *1* upon the locomotive of a passing train, the said lever *1* by its deflection actuating an arm *4*, previously placed by the driver in a suitable position within the slot 5 of a vertical lever *6*, the deflection of lever *6* operating to shut off the motive power and stop the train, or and to excite the steam, mechanical, electrical or other sonorous signal, substantially as and for the purposes herein described and shown.

In witness whereof we have hereunto set our hands in presence of two witnesses.

JOSEPH ROTH.
WILLIAM HELMKE.
